UNITED STATES PATENT OFFICE.

FLETCHER D. ALLISON, OF GALLIPOLIS, OHIO.

COMBINED BLACKING-CASE AND CHAIR.

SPECIFICATION forming part of Letters Patent No. 426,090, dated April 22, 1890.

Application filed April 8, 1889. Serial No. 306,393. (No model.)

To all whom it may concern:

Be it known that I, FLETCHER D. ALLISON, a citizen of the United States, residing at Gallipolis, in the county of Gallia and State of Ohio, have invented certain new and useful Improvements in a Combined Blacking-Case and Chair; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to a combined blacking-case and chair.

The improvement consists in the novel features, which will be hereinafter more fully described and claimed, and which are shown in the annexed drawings, in which—

Figure 1 is a side view showing the device arranged as a chair, by full lines, and as a chair, blacking-box, and foot-rest, by dotted lines. Fig. 2 is a perspective view showing the device unfolded.

The box A is provided at its front corners with the feet l and at its rear corners with the feet m, and is closed by the cover B, which is hinged to the end piece a and is adapted to be thrown out to form the foot-rest B', which is supported at its outer end by the legs b. The corner-posts, forming the feet m, are extended vertically some distance, and the seat E is hinged to the upper ends thereof. The rear end of the seat is provided with the supports N, which project above and below the same to form the leg-sections n and n', which are connected at their free ends by the cross-bar O and O', respectively. The leg-section

n is adapted to rest on the box or the feet l and support the seat, as shown most clearly in Fig. 1, or form the back of the seat when the latter is turned back, as shown by full lines in Fig. 2 and by dotted lines in Fig. 1.

The leg-section n', projecting in a diametrically-opposite direction from the leg-section n, supports the free end of the seat E when the latter is thrown back and forms a back for the seat when the latter is closed, as shown in

Fig. 1. The partition D divides the box into two compartments. The dirt-box d, placed in

the compartment nearer the end a, catches all dirt and dust from the shoes. The brushes and other articles are placed in the other compartment. The cover D' of the dirt-box when thrown back forms a shield to catch all dirt and direct it into the dirt-box, which latter can be removed at intervals and cleaned. The feet l have sockets p in their upper ends, into which corresponding projections P on the ends of the leg-sections n fit and hold the latter steady when resting on the said feet. The supports N are held to the box in any desired manner, preferably by the catch Q. The blacking-holder R is hinged to the rear side of the cover B and is held down on the said cover at its free end by the catch r. A slipper-box may be formed on the cover B, as shown by dotted lines in Fig. 1.

Having thus described my invention, what I claim, and desire to secure by Letters Patent, is—

1. The combination, with the box A, of the cover B, hinged to the said box and adapted to fold out in one direction to form a foot-rest, and the reversible seat having a leg-section which extends on opposite sides of the seat, and is adapted to form a back and leg support for the seat in either of its positions, having a hinged connection between it and the box and adapted to open and close in an opposite direction to the foot-rest, substantially as described.

2. The combination, with the box A, of the reversible seat having a hinge-connection between it and the said box and having a leg-section opposite the hinge-connection, which leg-section extends in opposite directions from the seat and forms a support and a back for the chair in either an open or a closed position, substantially as described.

3. The combination, with the box A, having feet i and m, the feet m projecting up higher than the feet i, of the reversible seat E, hinged or pivotally connected with the feet m, and having the leg-section N, which forms a back and a support for the chair in either an open or a closed position, the support N resting on the feet l when the seat is closed, substantially as described.

4. The hereinbefore-described combined chair and blacking-box composed of the box

A, having feet *l* and *m*, the feet *m* being higher than the feet *l*, the cover B, hinged to the box and having feet *b*, the reversible seat hinged or pivotally connected with the feet *m*, and 5 having the leg-section N, which forms a back and a support for the chair in either an open or a closed position, substantially as described.

In testimony whereof I affix my signature in presence of two witnesses.

FLETCHER D. ALLISON.
